UNITED STATES PATENT OFFICE.

EINAR UFFELMANN, OF NEW YORK, N. Y.

CONTAINER.

1,309,376.

Specification of Letters Patent. Patented July 8, 1919.

Application filed November 21, 1917. Serial No. 203,240.

To all whom it may concern:

Be it known that I, EINAR UFFELMANN, a citizen of the United States, and a resident of the borough of Manhattan, city and 5 State of New York, have invented certain new and useful Improvements in Containers, of which the following is a specification.

My invention relates to containers and more particularly to containers made of a 10 soft material from which the contents are ejected by compression of the sides, *e. g.*, tooth paste tubes, and is characterized by the provision of a neck for such containers and a longitudinally slidable cap adapted to act 15 as a closure for the orifice from which the contents are ejected.

One form of tooth paste tube and the one which probably is in more general use than any other form has been provided with a 20 screw cap. A screw cap is inconvenient to manipulate, requiring usually both hands of the operator, the threads are liable to be stripped, and the cap lost.

One form of tooth powder container has 25 been provided with a neck having an opening and a rotatable cap having openings on said neck, the openings in the neck and cap being adapted to be brought into registry by the rotation of the cap.

Another form of tooth powder box has 30 been provided with a longitudinally slidable cap operating within an upstanding peripheral flange secured to the shoulder of the box. A structure of this character 35 would not, however, be adapted for use with tubes having soft metal sides in which the contents are ejected by compression as the accidental compression of such sides would force up the cap by the pressure of the contents against the cap and permit the contents 40 to issue from the container. The closing of the cap would also present objectionable features when used with paste as the downward pressure of the cap would force an additional and undesired quantity of the contents 45 from the container.

In my invention, I have overcome to a great extent the objections above enumerated by providing an upstanding neck for the 50 container which acts as a reservoir for the contents and prevents the pressure thereof from acting directly against a cap which is longitudinally slidable thereon, in the direction in which said cap is adapted to 55 slide and preventing the cap from directly pressing on said contents when the cap is

pressed down. My structure is more conveniently operated as the cap may be closed by pressing the cap against some convenient object, thus obviating the necessity of the 60 operator employing both hands, as is necessary in the first and second structures above referred to; there are no threads to strip and the cap, being non-separable from the container, cannot be lost.

Other objects of my invention will more fully appear in the following description of the drawings accompanying this specification:

Figure 1 is a side elevation of one example of my invention showing a vertical section of the cap; Fig. 2 is a section of Fig. 1 on the line 2—2; Fig. 3 is a vertical section of one example of my invention; Fig. 4 is a side elevation of a modification of my invention with one of the elements partly broken away; Fig. 5 is a vertical section of the modification shown in Fig. 4 and Fig. 6 is a section of Fig. 5 on the line 6—6.

Referring to the drawings, a container 5, 80 preferably formed of soft metal such as lead, has an upstanding neck 6 having an opening 7 and provided with a longitudinally disposed groove 8, extending from the upper edge of said neck to a position approximately half way between the upper edge of the neck and the top of the container, and a longitudinally disposed groove 9 extending from a position below the top edge of the neck 6 to the top of the container 5. The 90 grooves 8 and 9 are joined by a by-pass groove 10. Co-axial with the neck 6 is a cap 11 of the usual construction having an in-turned lug 12 adapted to engage the groove 8 when in operative position. A modification of my invention, shown in Figs. 4, 5 and 6, shows a neck 13 similar to the neck 6 described for the modification shown in Figs. 1, 2 and 3 and provided with oppositely disposed longitudinal grooves 15 and 16. Co- 100 axial with the neck 13 is a cap 14 having in-turned lugs 17 and 18 adapted to engage respectively the grooves 15 and 16.

In assembling the device shown in Figs. 1, 2 and 3, the lug 12 is placed in a position 105 to engage the groove 8, the cap then pressed downwardly until the lug is opposite the by-pass groove 10. It is then rotated until the lug 12 is in the groove 9 when the cap may be moved longitudinally away from the container 5, thus exposing the by-pass groove 10 and portions of the grooves 8 and 9.

In order to prevent the cap from becoming disengaged from the container 5, the bypass groove may be closed in a suitable manner such as, for instance, by placing therein a drop of solder or by breaking down the wall of the groove so that the said wall partially covers and obstructs it. In this way the lug 12 is confined to the groove 9 and the cap 11 is prevented from becoming separated from the neck 6 of the container 5, while the cap 11 is longitudinally slideable on the neck 6 and the opening 7 may be covered or uncovered at will. In the modification shown in Figs. 4, 5 and 6, the cap 14 having the lugs 17 and 18 in alignment with the sides thereof so that the cap may be slipped over the top of the neck 13, are placed over the neck 13 of the container 5. The lugs 17 and 18 are then turned in to occupy a position substantially as shown in the Fig. 5, so that they engage the grooves 15 and 16, as hereinbefore described. The cap 14 is prevented from becoming separated from the container 5 by the lugs 17 and 18 striking the stop walls at the upper end of

the grooves, as will be readily apparent from an examination of the drawings. It is, of course, obvious that instead of employing lugs I may create depressions in the walls of the cap.

Various modifications may be made in the details of my invention without departing from the spirit of the appended claim.

I claim:

A container having a neck closed at the top and provided with a discharge opening in the side thereof communicating with the interior, a closure cap comprising an imperforate sleeve linearly slideable upon said neck so as to cover said opening in its inner position and uncover the opening in its outer position, the adjacent peripheral surfaces of neck and cap in the vicinity of the opening being at all times in close contact, and means for limiting the extent of outward movement of the cap.

In testimony whereof I have hereunto set my hand.

EINAR UFFELMANN,
